UNITED STATES PATENT OFFICE

WILLIAM H. KING, OF WEED, CALIFORNIA

PANEL DOOR CONSTRUCTION

Application filed February 24, 1931. Serial No. 517,775.

This invention relates to wooden doors and has for its objects an improved construction whereby the panels or inner frames are more easily affixed in place, and whereby the use 5 of nails is avoided in securing the panel molds, also a construction which facilitates the manufacture of raised molding doors.

In the drawings accompanying this specification Fig. 1 is a vertical cross section of 10 a one panel door showing my improved construction.

Fig. 2 is a similar view of what is known as an inner frame door made in accordance with my invention.

15 Fig. 3 is a similar view of a one panel door showing a modified form of the invention.

The common construction of wooden doors includes an outer frame which is grooved around its inner edge to receive a panel, and 20 the margins of the panels are finished either by tacking strips of molding in place, or by running the molding directly on the inner edges of the frame.

25 In my improved construction I provide interlocking moldings which are applied from opposite sides of the frame to interlock with one another in a glue joint and hold the panel between them, thus doing away with nails, or running the moldings on the frame.

30 In the figures 1 represents the door frame which may have one panel opening 2 or any number of them and which frame may further be a simple solid section as shown or built up out of any number of pieces as is 35 common in the better grades of doors.

The panels of the doors are designated 3, and in Fig. 1 these panels are shown held in place by means of moldings 4 and 5 applied from opposite sides of the frame and formed 40 to overlap the frame at 6 and with interlocking tongues and grooves 7, 8, and also formed to provide a groove 9 to receive the panel.

In this figure the tongue and groove are shown slightly beveled to produce a tight fit 45 and in assembling the parts the molding joints and the joint between the moldings and frame are glued, though the groove for the panel may be left free of glue if desired.

The ornamental part of the moldings may 50 of course be of any desired form and the mold-

ings may project beyond the faces of the door frame any desired distance to give the raised molding effect.

In Fig. 2 the interlocking molding sections are designated 4' and 5' and are the same as 55 shown in Fig. 1 except that the tongue and grooves are not shown tapered. In this view the moldings do not directly hold the panel 3, but hold an inner frame 10 which in turn holds the panel either in a plain groove as 60 shown or by further use of interlocking moldings as at 4' and 5'. In this view the whole insert, i. e., the inner frame 10 plus the panel 3 may be considered as a "panel" insofar as 65 the main or outer frame 1 of the door is concerned.

In Fig. 3 I show a modification of the invention in which the applied moldings 4", 5" are not made with integral tongues as in Figs. 1 and 2, but both are precisely alike and run 70 with a simple groove 11 into which is fitted a separate flat strip 12, the parts being glued and tightly forced together when assembling as described for Fig. 1.

With either modification the frame of the 75 door is made first and the moldings are mitred at the corners to fit the openings in the frame and forced together from opposite sides of the frame with glue in the joints, after first laying the panels in place in the rabbet 80 13 formed in the inner corner of one member of the molding.

While I show a clearance at 14 in the drawings and with the moldings tight against the panels, this clearance may be omitted and the 85 panels left slightly free if desired.

In my claims, the word "panel" is to be considered as also including the assembly of inner frame 10 of Fig. 2 when such construction is used.

90 I claim:—

1. A panel door comprising a main frame with an opening for the panel, moldings fitting within the opening on opposite sides of 95 and overlapping the frame of the door, a panel embraced by the moldings and a lock joint on the moldings between the panel and the door frame.

2. A panel door comprising a main frame with an opening for the panel, moldings fit- 100

ting within the opening on opposite sides of and overlapping the frame of the door, and a panel embraced between and by the moldings, said moldings formed with interlocking 5 tongues held together in a glue joint.

3. A panel door comprising a main frame with an opening for the panel, moldings fitting within the opening on opposite sides of and overlapping the frame of the door, a panel 10 embraced between and by the moldings, and interiorly interlocking means holding said moldings in clamping relation to said frame.
